UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,335,135.

Specification of Letters Patent. Patented Mar. 30, 1920.

Application filed May 20, 1918. Serial No. 235,525.

To all whom it may concern:

Be it known that I, CLARENCE C. STIRLING, a citizen of the United States, residing at Hartford, in the county of Hartford and 5 State of Connecticut, have invented certain new and useful Improvements in Electric Switches, of which the following is a specification.

This invention relates to electric switches, 10 the object of the invention being to provide an article of this character which is simple in construction, and positive, certain and effective in action.

In the drawings accompanying and forming 15 part of the present specification I have shown a form of embodiment of the invention which I will set forth fully in the following description. I am in no sense restricted to this particular disclosure; I may 20 depart therefrom in several respects within the scope of the invention defined by the claims following said description.

Referring to said drawings:

Figure 1 is a vertical section of a switch 25 involving the invention.

Fig. 2 is a section on the line 2—2 of Fig. 1, looking in the direction of the arrow.

Fig. 3 is a horizontal section on the line 30 3—3 of Fig. 2, looking in the direction of the arrow.

Like characters refer to like parts throughout the several views.

The switch is of magneto-mechanical type, 35 being of such character that the lines of magnetic force can be utilized to effect the movement for illustration of a magnetic conducting body. This magnetic conducting body is free to move in the vicinity of the lines of force emanating from the poles of 40 a magnet. In the present case there are two armatures, the relation being such that as one approaches the poles of the magnet, the other is receding therefrom, the result being there is a pull as well as a push upon the 45 movable member of the structure of whatever form it may take. This movable member is also positively held in its respective positions. In the present case the initial movement as I might consider it, of a circuit 50 controller is effected independently of the magnetic action, the remainder being magnetically obtained. The parts may be in-

corporated in switches of radically different kinds. As shown they are embodied in a pendent switch.

The carrier for supporting the different parts may be of any convenient kind. That shown is denoted in a general way by 2 and comprises a base 3, a body 4 and a cap 5, all generally of some suitable insulating 60 material. The base 3 as shown is in the form of a disk, set substantially in the lower part of the cylindrical body 4 which has a threaded connection exteriorly thereof at its upper end with the cap 5. As will be 65

understood from the observations already made, the switch comprises in its makeup a magnet of any one of several kinds. I have in fact obtained excellent results from the use of a permanent magnet, and when such 70 a part is used, it may be any one of different types. The magnet shown for this purpose is denoted by 6 and is of horse-shoe form with its limbs extending upward and its base resting on the bottom 3. Although the 75

magnet is shown as stationary or fixed, this may not always be necessary. There is mounted on said bottom 3 a bracket 7 having outwardly extending feet 8 perforated

to receive screws 9 by which said bracket 7 80 is fastened substantially to the bottom 3. Associated with the bracket 7 or more prop-

erly with the body thereof is the plate 10, this plate 10 and the bracket jointly receiv-

ing or clamping between them the lower 85 portion of the magnet 6, the bracket 7 and plate 10 having registering perforations

which receive the screw 11 furnished with a nut 12 which when set draws the bracket and plate in clamping relation with the interposed magnet. Between the bracket and plate are interposed sheets as 13 and 14 of 90 suitable insulating material as mica.

As will be inferred, the circuit controlling or switching member may be of any one of 95 several different forms. That shown is denoted in a general way by 15 and is oscillatory or swinging. It is shown in the "on" or closed relation by dotted lines in Fig. 2 and by full lines in said view in the "off" 100 or open relation. As shown the body of the circuit controlling member consists of an elongated strip doubled on itself to produce the eye or sleeve 16, the shank 17 and the

- upwardly diverging branches 18 and 19, the latter in turn terminating in eyes 20 which receive the armatures 21 and 22 respectively. As will be evident these armatures are movable and although this is the preferred condition, it may not be always necessary. The portions of the body 17 are for security held in substantial relation with each other by a rivet 23. The upper portion of the bracket 10 7 has ears 24 which are located between the branches of the magnet 6 and which receive between them the pin 25 constituting a suitable pivot for the circuit controlling or switching member 15, said pivot or pin extending through the eye or sleeve 16 to which I have already referred, and which as will be clear provides a convenient way of providing for the necessary swing of the circuit controlling or switching member. 15 20 While the magnet has two armatures, and while this is a quite desirable construction, it is not always necessary that they be duplicated or further increased because there may be conditions where a single armature 25 will answer the purposes. Preferably but not essentially each armature is round in cross section or is practically cylindrical, as one of this form is held more firmly to the poles of the magnet than a flat one and is 30 also detached with greater difficulty. In view of this circumstance, I increase the suddenness of movement at the inception of a stroke, which is so desirable in a quick break switch. 35 The leads to the switch are designated by 27 and 28, and they extend through an opening as 29 in the cap 5, their bared lower ends being wrapped about screws as 30 and 31 threaded through the horizontal parts of 40 brackets as 32 and 33, the vertical parts of said brackets receiving screws as 34 and 35 by which the brackets in question are held in place in the cylindrical shell 4. The screw 31 extends through the body 45 of a contact member 35, which body fits virtually flatwise against the horizontal part of the bracket 33. This contact member 36 shown as fixed is provided as represented with three branches or fingers 37, 38 and 39, 50 the two outer branches 37 and 39 as will be clear, pressing on the upper ends of the limbs of the magnet 6 so that as will be hereinafter made obvious when the switch is in the closed relation, the upper ends of 55 the magnet will carry some of the current. From the bracket 32 to which it will be remembered the wire 27 is electrically connected, a conductor or wire as 40, is electrically connected and is wrapped around 60 the screw 11, the switching member 15 being connected electrically with said screw 11. The actuator for the switching member is denoted in a general way by 41 and is as shown of push type, consisting of an inter-

mediate body 42 and the insulating buttons 65 43 and 44 on the body, the buttons or finger portions 43 and 44 extending freely through diametrically opposite perforations in the cylindrical shell 4. The intermediate body 42 as will be seen on inspection for instance of Fig. 2 extends freely through an opening or perforation 46 in the body or main portion of the switching member. The actuator 41 is provided with actuating portions 47 and 48 respectively between which the switching member 15 is situated. The full lines in Fig. 2 show the parts in the off positions, the contactor or armature 22 at this time being entirely free of the contact finger 38, the armature 21, however, being in magnetic contact with the magnet 6. It will be supposed that it is desired to obtain the "on" relation. In this event the following procedure may be adopted: The actuator 41 for illustration by manipulation will be moved toward the left in Fig. 2, and after it has moved a certain distance the actuating portion or shoulder 48 will engage the body 17 of the switching member, so that on the continuation of such further movement, the switching member will be suddenly operated, thus positively moving the armature 21 away from a strong magnetic field and the armature 22 to a strong field. As said armature 95 22 approaches the strong field, said armature will be attracted rapidly by the magnet and will as a consequence engage the finger 38 of the contact member 36 to close the circuit as illustrated by dotted lines in said Fig. 2. 100

The use of a multi-pronged contact member as 36 has its advantages. This contact member has three branches or prongs already briefly considered, as 37, 38 and 39, the branches or prongs 37 and 39 being at all times against and in electrical contact with the limbs of the magnet 6, so that when the switch is closed for instance as shown by dotted lines in Fig. 2, the current passes through the armature 22, the upper portions of the limbs of the magnet and the branches or prongs 37 and 39. In view of this branching or division of the current, I am enabled to make the branch or prong 38 of quite light spring effect, a large part of the current traversing the magnetic contact portions and avoiding the light spring as 38 which is practically used only in breaking. I can also break with little arcing. As a matter of fact the break is accomplished in a magnetic field, so that creation of sparks is reduced. 110 115 120 125

While the initiating of the action in the present case is accomplished through an actuator as 41, this actuator has a lost motion connection with the circuit controlling or switching member 15. After the actuator

has moved a slight distance, it encounters the switching or circuit controlling member, which is obviously resilient so as to tension the circuit controlling member and the latter in turn imparts to the armatures the necessary movement. The armature 21, it will be understood, is insulated from the circuit controlling or switching member, and this is shown clearly in Fig. 2. The armature 22 is obviously in electrical connection with the switching member. When the switch is in the on relation as shown by full lines in Fig. 2, current will pass through the wire 27, bracket 32, wire 40, plate 7, switching member 15, armature 22, contact member 36 to wire 28.

What I claim is:

1. The combination of a permanent magnet, a contact provided with a plurality of branches at least two of which are against the poles of the magnet and another of which is free of said poles and is springy, an armature for the magnet, adapted to bridge the poles of the magnet and at the same time to engage said free branch, and circuit-controlling means coöperative with said armature.

2. The combination of a permanent magnet of horse shoe form, a contact provided with a plurality of branches at least two of which are against the poles of said magnet and another of which is free of said poles and is springy, an armature for the magnet, adapted to bridge the poles of the magnet and at the same time engage said free branch, and circuit-controlling means coöperative with said armature.

3. The combination of a magnet, a contact provided with a plurality of branches at least two of which are against the poles of the magnet and another of which is free of said magnet and between said poles, an armature for the magnet adapted to bridge the poles of the magnet and at the same time to engage the free branch of the contact, and circuit-controlling means coöperative with said armature.

4. An electric switch comprising a magnet, a spring element in coöperative relation and in multiple with said magnet, an armature to engage the magnet and the spring, means for moving the armature first free of the magnet and afterward free of the spring to reduce sparking, and circuit-controlling means coöperative with said armature.

5. The combination of a permanent magnet, a spring element in coöperative relation and in multiple with said magnet, an armature to engage the magnet and the spring, means for moving the armature first free of the magnet and afterward free of the spring to reduce sparking, and circuit-controlling means coöperative with said armature.

6. The combination of a magnet, a contact provided with a plurality of branches at least two of which are against the poles of the magnet and another of which is free of said magnet, between said poles and in the form of a spring, an armature for the magnet adapted to bridge the poles of the magnet and at the same time to engage the spring branch of the contact, means for moving the armature first free of the magnet and afterward free of the spring branch to reduce sparking, and circuit-controlling means coöperative with said armature.

7. The combination of a magnet, a contact provided with a plurality of branches at least two of which are against the poles of the magnet and another of which is free of said poles, a movable member provided with separate armatures for said magnet one of them insulated from the movable member and the other in electrical connection therewith, means for causing said movable member to operate for carrying one armature out of the field of said magnet and for carrying the other into said field, the armature which is in electrical connection with said movable member when attracted by the magnet, engaging the free branch of said contact.

8. The combination of a permanent magnet having two legs, a contact member provided with three branches, two of which engage said legs, and the other of which is between the same, an armature, a carrier for the armature, means for operating the carrier to cause the armature to be attracted by the legs to bridge the same and at the same time position the carrier between the legs, and circuit controlling means governed by the armature.

9. The combination of a permanent magnet having two legs, a contact member provided with three branches, two of which engage said legs, the other being between the legs and resilient, an armature, a carrier for the armature, and means for operating the carrier to cause the same to enter between the legs and engage the intermediate branch and at the same time the armature to engage the legs, and circuit controlling means coöperative with the armature.

10. The combination of a permanent magnet, a resilient contact in electrical connection with said magnet, an armature for the magnet adapted when attracted thereby to bridge the poles of the magnet and to be also in electrical connection therewith and with the contact, means for moving the armature first free of the magnet and afterward free of the resilient contact to reduce sparking, and circuit-controlling means coöperative with said armature.

11. The combination of a permanent magnet, a contact provided with branches two

of which are against the poles of the magnet and the other of which is between said poles, a rocker having branches provided with armatures one in electrical connection therewith and the other insulated therefrom, a manually operable member for operating the rocker to move one armature into and the other out of the field of the

magnet, and circuit-controlling means co-operative with the rocker.

In testimony whereof I affix my signature in the presence of two witnesses.

CLARENCE C. STIRLING.
